(57) **CLAIM**

The ornamental design for an edge beveler, as shown and described.

DESCRIPTION

FIG. 1 is a front perspective view of an edge beveler showing my new design;

FIG. 2 is a front view thereof;

FIG. 3 is a rear view thereof;

FIG. 4 is a right side view thereof;

FIG. 5 is a left side view thereof;

FIG. 6 is a top view thereof;

FIG. 7 is a bottom view thereof; and,

FIG. 8 is a rear perspective view thereof.

The broken lines in FIGS. 1, 6, and 8 are included for the purpose of illustrating the environment of the claimed design, and form no part of the claimed design.
